(57) **CLAIM**

The ornamental design for a component of a non-electric coffee grinder, as shown and described.

DESCRIPTION

FIG. 1 is a top, front, and right-side perspective view of a component of a non-electric coffee grinder, showing my new design.

FIG. 2 is a bottom and rear perspective view thereof;

FIG. 3 is a top plan view thereof;

FIG. 4 is a front elevational view thereof;

FIG. 5 is a rear elevational view thereof;

FIG. 6 is a left-side elevational view thereof; and,

FIG. 7 is a right-side elevational view thereof.

1 Claim, 7 Drawing Sheets
